UNITED STATES PATENT OFFICE

108,108

DESIGN FOR A ROAD SIGN

Lottie Marie Summers, Dayton, Ohio

Application October 28, 1936, Serial No. 65,549

Term of patent 3½ years

To all whom it may concern:

Be it known that I, Lottie Marie Summers, a citizen of the United States, residing at Dayton, in the county of Montgomery and State of Ohio, have invented a new, original, and ornamental Design for a Road Sign, of which the following is a specification, reference being had to the accompanying drawing, forming part thereof.

The figure is a front elevational view of a road sign, showing my new design. The article is flat and of no appreciable thickness.

I claim:

The ornamental design for a road sign, substantially as shown and described.

LOTTIE MARIE SUMMERS.
